JACQUES RISLER, OF PARIS, FRANCE, ASSIGNOR TO RISLER CORPORATION OF AMERICA,
OF KANSAS CITY, MISSOURI, A CORPORATION OF DELAWARE

RECTIFYING TUBE

Application filed August 1, 1927, Serial No. 203,788, and in France June 3, 1927.

My invention relates to vacuum tubes for rectifying alternating current, and more particularly to tubes with electrodes of unequal sizes or shapes.

5 It is already known that when an electric current of suitable strength is passed through a vacuum tube having two electrodes of very unequal size the smaller electrode will become hot while the larger electrode remains relatively cool. In such a state the tube acts as a thermionic valve with the smaller electrode as cathode. A serious drawback to the practical employment of such tubes is the adsorption of gas by the 10 metal of, and from, the hot cathode. This adsorption reduces the pressure of gas in the tube and causes the resistance of the tube to rapidly increase with use.

The object of the present invention is to 20 obviate this difficulty and furnish a rectifying tube whose resistance remains approximately constant over a long period of use.

My invention comprises a vacuum tube with one or more cathodes of such a shape 25 that they can be hollowed out, the hollows containing a substance which liberates a gas on heating. In use the cathodes become hot and cause gas to be liberated from the material contained within them, this evolved gas 30 escaping to the main body of the tube through a suitable opening or openings in the walls of the cathodes. The gas so liberated off-sets the effect of the adsorption of gas by the metal of the cathode.

35 One form of my invention is represented diagrammatically in the accompanying drawing. This form is a double cathode tube suitable for rectifying both halves of the alternating current cycle.

40 The glass bulb, 1, is an ordinary lamp bulb. The cathodes, 2, are cylindrical in form and bored through the center with holes, 3, which contain the material that liberates gas on heating. Near the top the electrodes, 2, 45 are perforated with holes, 4, through which the gas liberated from the material in the holes, 3, may escape into the bulb, 1. The anode, 5, has a surface relatively much greater than that of the cathodes, 2.

50 The relative sizes of the cathodes 2 and

the anode, 5, may be varied widely. Also the distance between the ends of the cathodes, 2, and the anode, 5, may be varied. For a tube which will carry forty to sixty milliamperes the cathodes may suitably have an outside diameter of about 0.5 mm. and a length of 2 to 3 cm. The anode would then suitably have an exposed area of about 4 cm². For such a tube the distance between the ends of the cathodes and the anode surface may be 2 to 4 mm.

55 The anode, 5, may be of any stable metal; soft iron is suitable. The cathodes, 2, should preferably be made of some high melting conductor such as platinum or tungsten.

60 A variety of materials may be used in the holes, 3. Particularly suitable are salts of the alkaline earths and carbon compounds, such as anthraquinone, which have very low vapor pressures. When salts of the alkaline 65 earths are used they should preferably be finely divided.

65 Any stable gas may be used within the bulb. Its pressure should be such that the tube has as little resistance to the current as possible, and will, therefore, lie usually between 2 and 10⁻⁴ mm. of mercury.

70 What I claim and desire to secure by Letters Patent is:

75 A rectifying tube comprising a bulb evacuated to 2 to 10⁻⁴ mm. containing an anode 80 with an exposed surface of substantially 4 cm², and two hollow perforated cathodes each substantially 0.5 mm. in diameter and 2 cm. long and placed with their ends 2 to 4 mm. 85 from the anode surface, the hollows in the cathodes containing an alkaline earth salt.

85 In testimony whereof I affix my signature.

JACQUES RISLER.
